CLAIM

The ornamental design for a spacecraft with retractable solar sails, as shown and described.

DESCRIPTION

FIG. 1 is a top-front-top perspective view of a spacecraft with retractable solar sails in a deployed sail configuration showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a top-front-left perspective view of the spacecraft with retractable solar sails in a retracted sail configuration;

FIG. 10 is a bottom-rear-right perspective view thereof;

FIG. 11 is a magnified view of a deployed solar sail taken about circle 11 in FIG. 1; and,

FIG. 12 is a magnified view of a retracted solar sail taken about circle 12 in FIG. 9.

The broken lines illustrate the periphery of the enlarged views of the spacecraft with retractable solar sails and form no part of the claimed design.

1 Claim, 12 Drawing Sheets
